COMBINED CLOSURE AND AIR HOSE DUMMY

Sylvester L. Joiner, Sweetwater, Tex.

Application June 8, 1943, Serial No. 490,087

3 Claims. (Cl. 285—58)

This invention relates to a combined closure and air hose dummy, and it is an object of the invention to provide an air hose dummy coupling including a rubber gasket to assure a tight connection when the dummy coupling is applied and whereby a tighter closure is effected as the dummy coupling interlocks with the hose coupling head.

It is an important object of the invention to provide a dummy coupling to be applied at the rear end of a train and which serves to so close or seal the air line as to eliminate air leakage.

In connection with freight trains, the angle cock valve of the caboose is turned with great frequency resulting in relatively rapid wear due to rust, grit and other foreign matter scratching the side wall of the valve when the valve is opened up to let air out after the train has reached its destination and the engine is taken off. The air pressure in the line is of such power as to cause the sand and the like to cut the valve as it opens. It is a purpose of the present invention to provide a dummy coupling which will obviate these disadvantages and thereby materially prolong the life of the parts of the air system, such as the angle cock valve, and also the parts of the air pump or compressor on the locomotive, as with the use of my improved dummy coupling there will be no air leak and particularly when the air has reached that pressure, as eighty pounds in the train line, at which the pump will automatically stop.

The invention consists in the details of construction and in the combination and arrangement of the several parts of my improved combined closure and air hose dummy whereby certain important advantages are attained, as will be hereinafter more fully set forth.

In order that my invention may be better understood, I will now proceed to describe the same with reference to the accompanying drawings, wherein:

Figure 1 is a fragmentary view in elevation illustrating a dummy coupling constructed in accordance with an embodiment of my invention and in applied position.

Figure 2 is an enlarged sectional view taken substantially on the line 2—2 of Figure 1, the regular coupling being indicated by broken lines.

Figure 3 is a view in top plan of the dummy coupling as illustrated in Figures 1 and 2.

Figure 4 is a fragmentary view in side elevation illustrating a dummy coupling constructed in accordance with another embodiment of the invention.

Figure 5 is a fragmentary view in top plan of the device as illustrated in Figure 4.

Figure 6 is a fragmentary view in end elevation of a dummy coupling constructed in accordance with another embodiment of the invention.

Figure 7 is a fragmentary view in side elevation of the structure as illustrated in Figure 6.

Figure 8 is a view partly in section and partly in elevation illustrating a coupling constructed in accordance with a still further embodiment of the invention, and in applied position, and

Figure 9 is a view in top plan of the dummy coupling illustrated in Figure 8, unapplied.

In the embodiment of the invention as illustrated in Figures 1 to 3, 1 denotes an air hose section at the rear or caboose end of a train and which carries a coupling head H of a conventional type and with which is adapted to be interlocked the dummy coupling D to effectively close the air line. This dummy coupling D includes a head 2 similar to the conventional head H and is provided in its central portion with a rubber gasket 3 for coaction with the rubber gasket 4 of the head H when the dummy coupling D is applied, thereby providing a rubber-tight fit which assures an effective seal and thus eliminates such leakage of air which might result in an emergency application with resultant damage to equipment due to a quick stop.

30 The head 2 of the coupling D has an outstanding shank portion 5 closed against flow therethrough and this shank 5 is extended to provide a handle 6 to facilitate the application or removal of the coupling D. The outer or free portion of this handle 6 is provided with an opening 7 to allow convenient coupling with the handle 6 of an end portion of the dummy chain 8 for supporting the dummy coupling when not in use from a suitable adjacent portion of the caboose or other rolling stock.

In the embodiment of the invention as illustrated in Figures 4 and 5, the outer or closed end of the head 9 of the dummy coupling C has rigidly connected therewith an outstanding elongated link member 10 which also serves as a handle and is also of a character to readily permit the connection of a dummy chain therewith.

50 In the embodiment of the invention as illustrated in Figures 6 and 7, the shank portion 11 of the dummy coupling B is closed and the side of this shank portion 11 is provided with a laterally directed eye member 12 to which the dummy chain may be readily connected.

55 In the embodiment of the invention as illus-

trated in Figures 8 and 9, the dummy coupling A comprises an elongated and relatively narrow bar or member provided with the well known locking flanges 14 and 15 for coaction with the coupling head H'. Adapted to tightly interlock with the rubber gasket 16 of the coupling head H' is the rubber gasket 17 carried by and extending beyond the outer face of an annular plate 18. This plate 18 is provided with a central recess or socket 19 in which the gasket 17 snugly fits and the lower or inner portion of the side wall a of this recess or socket 19 is undercut to provide an annular recess or channel 20 in which is snugly received the outstanding surrounding flange 21 carried by and integral with the rubber gasket 17.

By the use of a dummy coupling including a rubber gasket for coaction with the rubber gasket of the usual or standard coupling head, the dummy coupling can be readily and easily applied or removed and when applied, assures such an interlocking connection to prevent leakage and which is more effective in use than the closing by the usual conventional angle cock valve.

From the foregoing description it is thought to be obvious that a combined closure and air hose dummy constructed in accordance with my invention is particularly well adapted for use by reason of the convenience and facility with which it may be assembled and operated.

What is claimed is:

1. A dummy air hose coupling, comprising an elongated member having locking flanges adjacent one end for connection with corresponding flanges of a standard coupling, the member having a substantially flat face between the locking flanges, said face having a circular recess formed therein and closed upon the side remote from said face against communication with the atmosphere, the inner wall of the recess having a circular channel cut therein, and a gasket fitted in the recess and having an encircling rib fitting in the circular channel, the gasket projecting beyond said face for tight engagement and coaction with the gasket of the standard coupling. 45

2. A dummy air hose coupling, comprising a relatively long flat plate body having a portion of one end obliquely extended to form a locking flange, a second locking flange integral with the side of the plate body remote from the first flange, the locking flanges being designed for connection with corresponding flanges of a standard coupling, the side of the plate from which the second mentioned flange extends and lying between the flanges, being designed to be positioned in opposed relation with the gasket of the standard coupling, an annulus secured to the said side of the plate between the flanges, the annulus being closed upon one side by the plate, the annulus having a circular channel cut in the inner face thereof, and a gasket fitted tightly in the annulus and having an encircling rib secured in said circular channel, the gasket extending beyond the side of the annulus remote from the plate for tight engagement and coaction with the gasket of the standard coupling.

3. A dummy air hose coupling, comprising a relatively long plate member having integral locking flanges adjacent one end for connection with corresponding flanges of a standard coupling, a face of the plate between the locking flanges having an area designed to position in opposed relation with the gasket of the standard coupling when the locking flanges are connected with the said corresponding flanges of the standard coupling, an annulus fixed to the plate over said area, the annulus having a circular channel cut in the inner face thereof, an eye forming member integral with the plate upon the side thereof opposite from said area for the attachment of a securing element to the coupling, and a gasket fitted in the annulus and having an integral encircling rib fitting in said circular channel, the gasket extending beyond the annulus for tight engagement and co-action with the gasket of the standard coupling. 40
